DOUBLE-DOOR STRUCTURE WITH
LATCHING MECHANISM

Charles G. Minor, Evanston, Ill., assignor of one half to Albert G. McCaleb, Chicago, Ill.; Harry H. Gmeiner, executor of said Charles G. Minor, deceased; Ruth F. McCaleb, executrix of said Albert G. McCaleb, deceased

Application November 29, 1947, Serial No. 788,830

6 Claims. (Cl. 20—16)

1

This invention relates to a double door structure with a latching mechanism for releasably holding the doors in their closed positions, and more particularly to such a structure which provides tight joints and avoids the necessity of a mullion between the doors.

It is a general object of my invention to provide a double door structure incorporating a latching mechanism constructed and arranged to avoid the use of a mullion and adapted to uses such as the closing of refrigerators and the like in which tight door joint seals are required.

As another object, the invention comprehends the provision of a double door structure embodying a latch mechanism for holding both doors closed and which is operable by a single release element for effecting the release and opening of both doors.

My invention further has within its purview the provision of a mullionless double door structure having a latching mechanism for holding the doors closed and wherein a tightly sealed joint is provided between adjacent edges of the doors by parts constructed and arranged to minimize friction and wear.

For another object, my invention comprehends the provision of an effective and efficient latch system for a mullionless double door.

Other objects and advantages of the invention will be apparent from the following description and the accompanying drawings, in which similar characters of reference indicate similar parts throughout the several views.

Referring to the five sheets of drawings,

Figs. 1 and 2 are respectively top plan and fragmentary front elevational views of a refrigerator cabinet or the like having thereon a double door structure and latch mechanism embodying a preferred form of my invention;

Figs. 3 and 4 are fragmentary side section views of my door and latch structures drawn to a larger scale than Figs. 1 and 2, and wherein the sections are taken substantially along a line between the doors and as indicated by the arrows 3—3 and 4—4 in Fig. 2;

Fig. 5 is a fragmentary sectional view taken substantially on a line 5—5 of Fig. 3 and in the direction indicated by the arrows;

Fig. 6 is a fragmentary sectional view similar to Fig. 5 but showing different operating positions of some of the parts;

Fig. 7 is a fragmentary sectional view wherein the section is broken and taken substantially as indicated by the lines 7—7 and accompanying arrows in Fig. 3;

2

Fig. 8 is a fragmentary and broken sectional view wherein the sections are taken substantially as indicated by the lines 8—8 and accompanying arrows in Fig. 7;

5 Fig. 9 is a fragmentary sectional view taken substantially as indicated by lines 9—9 and accompanying arrows in Fig. 4;

Fig. 10 is a fragmentary sectional view similar to Fig. 9 but indicating different operating positions of the parts; and

10 Fig. 11 is a fragmentary sectional view wherein the section is taken substantially as indicated by line 11—11 and accompanying arrows in Fig. 9.

Referring generally to the exemplary embodiment of my invention which is shown in the accompanying drawings for illustrative purposes, I have depicted the adaptation of my mullionless double door and latch structures to a refrigerator cabinet 15, although the use of such doors

20 and latch mechanisms with respect to other types of housings may readily suggest themselves. As depicted in Figs. 1 and 2, the refrigerator cabinet 15 has a compartment 16 opening outwardly at the front of the cabinet and adapted to be closed by doors 17 and 18. In the disclosed embodiment of my invention, the doors 17 and 18 are supported along opposite side edges with respect to the cabinet 15 by hinges 19 and 20 respectively. Thus the doors swing towards and from one

30 another between closed and open positions; in the former of which positions they are in substantially flush relationship and overlie marginal portions of the cabinet such as 22 and 23 in Fig. 1. Also, when closed, and when used on refrigerators

35 and the like, the joints between the doors and the cabinet are preferably sealed by resilient gaskets such as 24, and the joint between adjacent edges of the doors is desirably sealed by a resilient gasket such as 25. A manually operable handle 26 is mounted at a convenient position on the outer surface of one of the doors for effecting control of door latching mechanisms which will be described in detail and which releasably hold the doors in their closed positions without

40 the aid of a mullion between the doors.

45 Referring to the disclosed structure in greater detail, the doors 17 and 18, for adaptation to refrigerator service, are desirably made of sheet metal panels such as 27, 28, 29 and 30 suitably formed and secured together along adjacent outer edges by welded seams or the like, with the space between the panels filled with a suitable insulating material 32, as depicted in Figs. 5 and 6. At the edge of the door 18 opposite the hinge 20, 50 the panels 29 and 30 are joined by a sheet metal

strip 33 having side flanges 34 and 35 disposed between the panels to provide a channel 36 opening outwardly at the edge of the door. On the other door 17, the panel 28 has a portion 37 bent to form an edge surface for the door and having a flange 38 thereon which is secured to the margin of panel 27. At the mid-portion of the panel portion 37, as shown in Figs. 3 and 8, an opening 39 is provided adjacent a recess 40 to provide space for a latch mechanism 42.

As illustrated in Figs 5, 6, 9 and 10, the door 18 has a rocker plate 43 supported for limited rotational movement in the channel 36 by aligned upper and lower support bolts 44 and 45 respectively (Figs. 4 and 11), which support bolts provide an axis of rotational movement extending longitudinally of the edge of the door and located in the mid-portion of the channel 36. As illustrated, the rocker plate 43 is substantially co-extensive with the edge of the door and of a width such that it practically closes the opening of the channel 36 with only sufficient clearance along the side edges for free rotational movement of flanged edges 46 and 47 thereof between the flanges 34 and 35 which define the channel 36.

Upper and lower latch pawls 48 and 49 are secured to the inner surface of the rocker plate 43 near opposite ends thereof and in positions for releasable latching engagement with latch keepers 50 and 52 secured to the marginal portions 23 of the cabinet 15 by fastening means such as screws 53 (Figs. 4, 9, 10 and 11). In the illustrated embodiment of the invention, the latch pawls 48 and 49 are provided with integral flanges 54 and 55 respectively, which flanges fit against and are secured to the inner surface of the rocker plate 43. As shown in Figs. 9 and 10, substantially flat end portions such as 56 on the latch pawls project outwardly from the channel 36 through slots such as 57 in the side flange 34 of the channel on the inner surface of the door and present keeper engaging surfaces such as 58.

In my preferred construction and as indicated in Figs. 9, 10, and 11, the support bolts 44 and 45 have shoulders such as 59 adjacent threaded end portions such as 60 which extend through openings 62 in the latch pawls and are secured in position by fastening means such as nuts 63. Brackets such as 64 are secured to the sheet metal strip 33 within the channel and are provided with bearing bores such as 65 in which the bolts 44 and 45 are supported for rotational movement adjacent the outer surfaces of the latch pawls. Springs such as 66 surround projecting end portions of the bolts 44 and 45 adjacent the brackets 64 and have projecting end portions such as 67 and 68 which normally bias the rocker plate 43 to an angularly disposed position such that it faces somewhat outwardly of the door opening and has its outer end disposed within the channel 36, while its inner end projects outwardly of the channel as shown in Fig. 10.

Springs 66, as indicated, normally bias the rocker plate 43 and latch pawls 48 and 49 to positions such that they are disengaged from the latch keepers 50 and 52. Thus, the door 18 is normally released for swinging movement to its open position, and is only latched by the pawls and their respective keepers when the rocker plate is held in a latch engaging position against the biasing force of the springs 66.

In order to effect latching of the door 18 in its closed position relative to the cabinet 15, the door 17 has secured thereto near the inner margin of its exposed end surface a striker strip 69 which

is made of a relatively hard and durable material, such as phenol fiber or plastic, and is secured in position by fastening means such as screws 70. The striker strip 69 extends longitudinally along the inner end surface of the door at a position such that during the closing movements of the doors, or when the door 18 is closed and the door 17 moves toward it to closed position, the striker strip engages the projecting outer surface of the rocker plate intermediate the inner end thereof and its axis of rotational movement. By engaging the rocker plate in that position, the closing movement of the door 17 effects movement of the rocker plate and the latch pawls 48 and 49 against the biasing force of their springs and into positions such that the latch pawls engage their respective keepers to hold the door 18 in its closed position relative to the cabinet.

In order to provide an effectively sealed joint between the adjacent edges of the doors 17 and 18 when they are in their closed positions, a sealing strip 72 of resilient material is secured to and extends longitudinally along the outer marginal portion of the rocker plate 43, as well as across the upper and lower ends thereof, as depicted in Figs. 4, 9, 10 and 11. This sealing strip is desirably hollow and thus deformable to provide an effective area of surface engagement with the edge surface of the door 17, as shown in Figs. 9 and 11. Also as indicated in those figures, the sealing strip may be provided with integral and deformable mounting button portions 73 for engagement in suitable apertures 74 in the rocker plate to secure the sealing strip in place.

With the door 18 thus held in its closed position relative to the cabinet by the latch pawls 48 and 49 carried by rocker plate 43 and normally biased to a position for releasing the door, and since the latch pawls for the door 18 are controlled by the door 17, the door 17 may be latched in its closed position relative to the door 18 and the opening of both doors may be controlled by the single manually operable handle 26. In the disclosed embodiment of my invention, the latch mechanism 42 which holds the door 17 in its closed position relative to the door 18 includes an adjustable striker block 75 secured within a recess 76 formed in the mid-portion of the exposed outer surface of the rocker plate and carrying a roller 77 engageable with a latching surface 78 of a latch bolt 79. The striker block 75 is secured in position by fastening means such as screws 80 and has a recess 82 adjacent an inner corner thereof in which the roller 77 is carried for rotational movement by a pin 83; the length of the roller being ample for full engagement with the latching surface 78 of the latch bolt 79.

The latch bolt 79 is carried for limited rotational movement within and relative to a latch box 84 by a shaft 85. The latch box 84 has mounting flanges 86 on its front surface and is supported within the latch recess 40 in substantially flush relationship to the edge surface of the door by a plate 87 to which it is secured by fastening means such as screws 88; the plate 87 being secured to the edge surface of the door by fastening means such as screws 89 threaded into internal reinforcing strips 90. Compression spring 92 disposed within a recess 93 in the latch bolt 79 and projecting therefrom into engagement with the inner surface of the latch box biases the latch bolt to a position such that the latching surface 78 projects from the edge surface of the door through an opening 93 in plate

87 to a position for latching engagement with the roller 77 on the striker block 75.

The surface of the latch bolt adjacent the latching surface 78 is smoothly curved to serve as a cam surface adapted to engage the roller 77 during the closing movement of the door 17 when the latch bolt is extended, thereby to effect a retracting movement of the latch bolt until it has passed beyond the center of the roller. In a position opposite the exposed end of the compression spring 92 and displaced from the axis of the shaft 85, the latch box 84 is open and has movably mounted therein a hinge plate 94 carried relative to the box for swinging movement by a shaft 95. The inner surface of the hinge plate 94 normally engages a projecting lug 96 on the adjacent surface of the latch bolt, which lug presents a rounded surface adapted to have a cam action with the surface of the hinge plate during the movements of the latch bolt.

As depicted in Figs. 5, 6, 7 and 8, the exposed and manually operable handle 26 is secured to and carried by a cross shaft 97, which cross shaft, in turn, is supported for rotational movement in a bearing bore 98 which extends through a bearing block 99. As illustrated in Fig. 8, the bearing block 99 is secured to the outer surface of the door 17 by fastening means such as screws 100 threaded into a plate 102 inside the panel 28 of the door. On the side of the bearing block opposite the handle 26, the cross shaft 97 is secured to and carries a latch actuating lever 103 which extends through an opening 104 in the door panel 28 and normally engages the exposed outer surface of the hinge plate 94. As depicted in Fig. 3, a compression spring 105 mounted between an end portion 106 of a bracket 107 and an angularly disposed end portion 108 of a projecting portion 109 integrally formed on the end of the handle 26 normally biases the handle to a position such that a resilient bumper block 110 carried by the handle engages the panel 28 of the door 17. In this position, the lever 103 is retracted to an extent such that the latching surface 78 of the latch bolt 79 is extended. The bracket 107 has an end portion 112 which is secured to the panel 28 of the door 17. Also, a projecting portion 109 of the handle has an internal shoulder 113 engageable with the end portion 106 of the bracket 107 to limit the outward movement of the handle 26 to a position in which the latching surface 78 is released from the roller 77, and thus providing a stop permitting the use of the handle for the application of force to open the door after the release of the latch. In its latch releasing position, the handle 26 assumes a position substantially as indicated by dot and dash lines in Fig. 3 at 26a.

In order to improve the outward appearance of the door latch and mechanism and to cover the bearing block 99, as well as the ends of the cross shaft 97, lever 103 and handle 26, an escutcheon 114 is mounted over those parts. By preference, the bearing block is provided with angularly disposed wedge surfaces 115 onto which the escutcheon is placed by lateral sliding movement. When thus placed, the escutcheon is secured in position by fastening means such as a screw 116. For balance and appearance, a second escutcheon 117 is mounted in an aligned and adjacent position on the door 18. In this instance, a support bracket 118 is secured to the panel 30 of the door 18 by fastening means such as a screw 119 and has wedge surfaces (not shown) similar to those of the bearing block 99, upon which the

escutcheon 117 fits. Also, fastening means such as a screw 120 holds the escutcheon 117 in place. In my preferred structure, the escutcheon 114 has an internal boss 122, bored to provide a bearing 123 which receives and provides additional support for the projecting end of the cross shaft 97.

As indicated in Fig. 10, the door 18 which carries the rocker plate 43 is to be closed before or 10 somewhat ahead of the door 17. When thus closed, the delayed closing of the door 17 actuates the rocker plate to effect the latching engagement of the latch pawls 48 and 49 with their respective latch keepers 50 and 52. The same closing 15 movement of the door 17 effects engagement of the latching surface 78 with the roller 77 on the latch block 75 and thus latches the door 17 in its closed position relative to the door 18.

Outward movement of the handle 26 away from 20 the door 17 against the biasing force of the compression springs 92 and 105 retracts the latch bolt 79 by rotational movement thereof and thereby effects release of the latching surface 78 from the roller 77 on the latch block 75. Being thus 25 released, the manual force applied to the handle 26 for releasing the latch is also in a direction to start the opening movement of the door 17. When thus started, the opening movement of the door 17 is aided by the biasing force of the 30 spring 66 against the rocker plate 43 which is transmitted to the door 17 through the striker strip 69. The door 18, although released, remains substantially closed until manually opened, unless it is desired for some reason to apply there- 35 to a spring which will bias the door to an open position.

While I have illustrated a preferred embodiment of my invention, many modifications may be made without departing from the spirit of the 40 invention, and I do not wish to be limited to the precise details of construction set forth, but desire to avail myself of all changes within the scope of the appended claims.

Having thus described my invention, what I 45 claim as new and desire to secure by Letters Patent of the United States, is:

1. In a double door structure adapted tightly to close a door opening of a housing and to be latched in the closed position without the use of 50 a mullion between the doors in said opening, the combination comprising two doors hingedly supported at opposite edges for swinging movement toward and from one another between open and closed positions, said doors in their closed position being substantially flush with one another and having edges in adjacent relationship at the mid-portion of the door opening, a first latch carried by one of said doors and supported for swinging movement relative to said edge thereof, 55 said first latch being normally biased by a spring to a position in which said one of the doors is released for opening movement, a keeper secured to said housing in position for engagement by said first latch to hold the said one of the doors in the closed position, an actuating element on the other of said doors for effecting engagement of the keeper by said first latch when said doors are moved to their closed positions, a second latch on said other door positioned for engagement 60 with a keeper on said one of the doors and normally biased to a latching position for holding the other of said doors in the closed position, and means including a manually operable handle on said other of the doors for effecting release of 65 said second latch to free said other of the doors

for opening movement which results in movement of the actuating element away from the first latch and movement of said first latch by the spring to a position away from said keeper on the housing.

2. In a double door structure adapted tightly to close a door opening of a housing and to be latched in the closed position without the use of a mullion between the doors in said opening, the combination comprising two doors hingedly supported at opposite edges for swinging movement toward and from one another between open and closed positions, said doors in their closed position being substantially flush with one another and having edge surfaces in adjacent relationship at the mid-portion of the door opening, upper and lower latch elements mounted on a single support piece and carried by one of said doors for limited swinging movement relative to the vertical free edge of the door, said support piece being normally biased to a position in which said one of the doors is released for opening movement, keepers secured to said housing in position for engagement by said latch elements to hold the said one of the doors in the closed position, an actuating element on the other of said doors for effecting movement of said single support piece and latch elements to their keeper engaging positions when said other of the doors is moved to the closed position after movement of said one of the doors to its closed position, a second latch mounted on said other of the doors and engageable with a keeper on said one of the doors for holding the other of said doors in the closed position when moved thereto, and a manually operable handle on said other of the doors for effecting release of said second latch so that said other of the doors is free to open, thereby to effect separation of the actuating element from the single support piece and resultant release of the latch elements to release said one of the doors for opening movement.

3. In a double door structure adapted tightly to close a door opening of a housing and to be latched in the closed position without the use of a mullion between the doors in said opening, the combination comprising two doors hingedly supported at opposite side edges for swinging movement toward and from one another between open and closed positions, said doors in their closed position being substantially flush with one another, and having edges in adjacent relationship at the mid-portion of the door opening, a latch element including a latch pawl carried by one of said doors and supported for swinging movement relative to said edge and about an axis extending longitudinally of the mid-portion of the edge, said latch element being normally biased by resilient means to a position in which said one of the doors is released for opening movement, a keeper secured to said housing in position for engagement by said latch pawl to hold the said one of the doors in the closed position, an actuating element on the other of said doors in position to engage the latch element inwardly of said axis during inward swinging movement of said other of the doors for effecting swinging movement of said latch element and pawl into holding engagement with said keeper, a second latch on said other of the doors and engageable with a keeper on said one of the doors when both of the doors are closed for holding the other of said doors in the closed position, and means including a manually oper-

able handle on said other of the doors for effecting release of said second latch, thereby to release said other door for opening movement which results in separation of the actuating element from said latch element and release of said latch element for movement by the biasing force applied thereto.

4. In a double door structure as defined in claim 3, said second latch including a latch bolt mounted for swinging movement relative to the edge of said other of the doors between extended and retracted positions, a spring biasing the latch bolt to the extended position, and said keeper for the second latch including a roller engageable with the extended latch bolt.

5. In a double door structure adapted tightly to close a door opening of a housing and to be latched in the closed position without the use of a mullion between the doors in said opening, the combination comprising two doors hingedly supported at opposite edges for swinging movement toward and from one another between open and closed positions, said doors in their closed positions being substantially flush with one another and having edges in adjacent relationship at the mid-portion of the door opening, a first latch carried by one of said doors and including a latch element secured to a movable rocker plate, said rocker plate being supported for limited rotational movement about a fixed axis extending longitudinally along the mid-portion of the edge of the said one of the doors, said rocker plate also being normally biased to an angular position facing somewhat outwardly of said one of the doors and in which position of the rocker plate the door is released for opening movement, a keeper secured to said housing in position for engagement by said first latch to hold the said one of the doors in the closed position, an actuating element on the other of said doors for effecting engagement of the keeper by the first latch when said doors are moved to their closed positions, a second latch on said other door positioned for engagement with a keeper on said one of the doors and normally biased to a latching position for holding the other of said doors in the closed position, said keeper for the second latch being mounted in a recess in the rocker plate and movable with the rocker plate to a position for operative engagement with the keeper on said one of the doors when the doors are in their closed positions, and a manually operable handle on said other of the doors for effecting release of said second latch.

6. In a double door structure as defined in claim 5, said actuating element comprising a buffer strip secured to the edge of said other of the doors at a position aligned for engagement with said rocker plate during closing movement of the doors to effect movement of the rocker plate against the biasing force applied thereto.

CHARLES G. MINOR.
